UNITED STATES PATENT OFFICE.

CLARENCE S. STEWARD, OF CHATTANOOGA, TENNESSEE.

HEATING UNIT.

1,094,264.

Specification of Letters Patent. Patented Apr. 21, 1914.

Application filed December 9, 1913. Serial No. 805,587.

To all whom it may concern:

Be it known that I, CLARENCE S. STEWARD, a citizen of the United States, residing at Chattanooga, in the county of Hamilton and State of Tennessee, have invented certain new and useful Improvements in Heating Units; and I do hereby declare the following to be a full, clear, and exact description of the invention, such as will enable others skilled in the art to which it appertains to make and use the same, reference being had to the accompanying drawings, and to the letters and figures of reference marked thereon, which form a part of this specification.

This invention relates to certain new and useful improvements in heating units for electrical heaters and it has for its object the provision of a unit of this character constructed of suitable non-conducting material and of any desired shape, one of the faces of the unit being provided with grooves arranged in parallel relationship and extending transversely across the face of the unit, the said grooves being wider at the bottom than at the surface of the unit and with widened portion forming a compartment designed to receive a resistance wire, either coiled or in other form, thus retaining the wire against possible accidental displacement.

The invention has for a further object the improvement of units of this character, the improvement consisting essentially in the provision of either slots or openings communicating between the lower surface of the unit and the chamber containing the resistance wire, thus permitting a free circulation of air through the unit, the air in its passage being heated from the electric current and which unit also serves to be heated from contact with and proximity to the heated wire whereby the air may be drawn in from beneath the unit through the orifices provided below the wires and in passing over the heated wires through and around the heated unit will serve to elevate the temperature and cause a continuous circulation of heated air through the unit.

To these ends and to such others as the invention may pertain, the same consists of the novel construction and in the peculiar arrangement, combination and adaptation of parts, all as will be more fully hereinafter described, shown in the accompanying draw-

ings and then specifically defined in the appended claims. 55

The invention is clearly illustrated in the accompanying drawings which, with the numerals of reference form a part of this specification and in which:— 60

Figure 1 is a top plan view of a heat unit embodying the features of my invention. Fig. 2 is a bottom plan view of the same. Fig. 3 is a detail sectional view taken on line 3—3 of Fig. 1. Fig. 4 is a like view of a slightly modified form of construction and Fig. 5 is a sectional view on line 5—5 of Fig. 2. 65

Reference now being had to the details of the drawings by numeral, 1 designates a disk 70 constructed preferably of steatite or soap-stone or other noncombustible material adapted for the purpose. Disposed at intervals and extending transversely across the upper face of the disk are a series of parallel grooves 2, 2. These grooves are open at their ends and have their lower portions milled out to form an enlarged portion 3 designed for receiving the resistance wire 4. Each alternate end of the bars 5, which separate the parallel slots 2, is cut away, as shown at 6, 6, and within these cutaway portions are provided lugs 7, the upper face of which lugs or stops are disposed slightly below the face of the unit and serve to lock 85 the resistance wire against accidental displacement. 75

Directly beneath the enlarged portions or chambers and forming communication between the resistance wire chambers and the under face of the unit are provided contracted slots 8 connecting the wire chambers with the surface of the disk, as illustrated in Fig. 1, or, if preferred, communication between the wire chambers and the under surface of the disk may, in lieu of the slots, be obtained through perforations 9, such as illustrated in the modified form, Fig. 4. 90

While I have shown and described a unit of cylindrical form and prefer such construction, it is at once evident that the body of the unit may, if desired, be rectangular or elliptical or of any desired shape, or may be constructed of two or more pieces which, when suitably joined and held together by 100 means of a metallic rim or otherwise, will approximate the same result as obtained by the use of a single piece of material and my 105

invention contemplates such a modification.

From the foregoing description, the construction and the advantages derived from the use of the invention will at once be apparent.

What I claim to be new is:—

1. A heating unit for electric heaters comprising a single disk, one face of which has a series of grooves formed therein, each groove leading into a chambered portion of greater diameter than the width of said grooves, the bottom of each chamber having openings leading through the disk, affording means for introducing air into the chambers, said grooves adapted to contain resistance wires, substantially as shown and described.

2. A heating unit for electric heaters, the same comprising a disk having one of its faces provided with a series of grooves arranged in parallel relationship and communicating with chambers of greater di-

ameter than the width of the slots and designed to receive a resistance wire, said disk 25 being also provided with slots or air inlets disposed upon the under side thereof and communicating with the wire chambers, substantially as shown and described.

3. A heating unit for electric heaters, the same comprising a disk or body portion of electrically insulated and heat storing material, said disk having one of its faces provided with a series of slots disposed in parallel relationship and communicating with enlarged chambers adapted to receive resistance wires and the opposite side of the disk being provided with air passages communicating with the wire chambers, substantially 35 40 43 as shown and described.

In testimony whereof I hereunto affix my signature in presence of two witnesses.

CLARENCE S. STEWARD.

Witnesses:

IDA McCARRON,
J. H. WOODY.
